UNITED STATES PATENT OFFICE.

GEORGE H. GILBERT, OF GERMANTOWN, PENNSYLVANIA, ASSIGNOR TO
THE KILBOURN KNITTING MACHINE COMPANY, OF NEW BRUNSWICK,
NEW JERSEY.

SEAMLESS HOSIERY.

No. 822,044.

Specification of Letters Patent.

Patented May 29, 1906.

Application filed June 7, 1901. Serial No. 63,622.

To all whom it may concern:

Be it known that I, GEORGE H. GILBERT, a citizen of the United States, residing at Germantown, in the county of Philadelphia and 5 State of Pennsylvania, have invented certain new and useful Improvements in Seamless Hosiery; and I do hereby declare the following to be a full, clear, and exact description of the invention, such as will enable others 10 skilled in the art to which it appertains to make and use the same.

My invention relates to machine-made seamless hosiery, and has for its object the production of a stocking having improved 15 ornamental effects.

Hitherto manufacturers of ornamental seamless hose or stockings have been able to make the ornamental open-work, or lace-work on the front of the stocking only, and 20 such ornamental lace or open work began at the top of the stocking and continued down over the ankle and front of the foot to the toe portion. I am, however, able to produce an article of this class having a portion of 25 plain knitting at the top of the leg of the stocking, the leg composed of sections of lace-work alternating with sections of plain knitting around the entire leg, the heel and bottom of the foot and toe being made of plain 30 knitting, while the open-work sections are continued over the ankle and foot with a portion of plain-knitted fabric interposed between the lower end of such open or lace work sections and the toe.

35 In the drawing I have shown a stocking embodying my invention, the same being partially in perspective to show the ornamental section extending entirely around the leg.

40 In such drawing, A is the leg portion of the stocking, and B the foot portion. At the top of the leg portion is a plain-knitted portion a. Commencing at the point x x the leg of the stocking is formed of plain-knitted 45 portions c, united by open-work or lace sections c', the one alternating with the other entirely around the leg. The loops of the several courses forming one figure of the lace or open work are made as follows:

50 Starting at the plain section l, the thread forms a straight cross-thread e to the next plain section, crossing the space of one or more plain loops. A given number of plain loops is then made. The thread then makes a

further cross-thread to the next section of 55 plain knitting, and so on entirely around the leg of the stocking. On the next round the cross-thread e' is made in like manner. On the third round the cross-thread e² is made in the same manner. On the fourth round the 60 cross-thread is drawn down over the three cross-threads e e' e², forming the elongated loop d, as is well understood in the knitting of tuck fabrics. This is continued to the point marked y, where the heel is knitted of 65 plain loops. After the formation of the heel the knitting is continued, forming the bottom of plain loops and the top of the ornamental courses and plain sections, as herein-before set forth, until the point x is reached, 70 at which point a number of plain-knitted courses are formed entirely around the stocking. The toe is then completed with plain loops, thus forming a stocking which has the plain-knitted portion a, the leg of ornamental sections a', the heel b of plain loops, the bottom of the foot of plain knitting b', and, 75 the sections b² of plain knitting interposed between the ornamental courses and the toe b³ of the stocking. This stocking may be 80 made of one continuous thread, or it may be made by knitting the heel and toe of one thread and the remaining portions of the stocking from another thread, or it may be made by forming the heel and toe of one 85 thread and the other portions of the stocking knitted from two, three, or four other threads, as the manufacturer may prefer. The stocking may be knitted upon a machine constructed in the well-known manner 90 to produce tuck-knitting, provision being made for causing the needles of the front and back portions of the stocking to be thrown separately into operation to knit tuck or plain knitting as desired.

95 While I have described the ornamental effect as produced by employing in the ornamental figures the three cross-threads e e' e², with a fourth forming an elongated loop connecting and holding the others, this exact 100 proportion is not necessary or essential, as but one, two, or more of the cross-threads to every elongated loop may be employed to suit the taste or fancy of the manufacturer.

105 The arrangement of open-work spaces in respect to the plain-knitted portions may also be varied, and a single plain loop may be made between the lace-sections, giving the

stocking the appearance of being formed entirely of lacework, or this effect may be employed solely on the front of the stocking.

5 It will be understood that, if preferred, the lacework may begin with the top of the stocking and be continued to the toe; but this is not my preferred construction.

In the description herein given of the stocking embodying my improvements it is 10 assumed that the stocking is knit beginning at the top of the stocking and knitting toward the toe of the same; but it will be understood that such a stocking could be knit beginning at the toe, the latter being only a reversal of the former operation.

15 What I claim, and desire to secure by Letters Patent, is—

1. The herein-described machine-knit seamless stocking having open or lace work portions, and solid plain-knit portions preceding the lacework portions, substantially as described.

20 2. The herein-described machine-knit seamless stocking having open or lace work portions, and solid plain-knit portions preceding the open or lace work portions and solid plain knitting following the open or lace work portions, substantially as described.

25 3. The herein-described machine-knit seamless stocking having solid plain knitting at the top of the leg for the hem or welt and open or lace work following such hem, substantially as described.

30 4. The herein-described machine-knit seamless stocking having solid plain knitting and open or lace work alternating longitudinally of the stocking and having solid plain knitting for forming the joining at the toe of the stocking substantially as described.

35 40 5. The herein-described machine-knit stocking having a plain-knitted portion at the top of the stocking, and having an open-work portion in which there are dropped stitches, and a plain-knitted portion between the dropped stitches and the toe of the stocking, substantially as described.

45 6. A machine-knit seamless stocking having lacework on the back and front of the stocking and having the lacework extending 50 down upon the top of the foot of the stocking and having a plain-knitted portion preceding the lacework and a plain-knitted portion following said lacework, substantially as described.

55 7. A machine-knit seamless stocking having lacework on the back and on the front of the leg of the stocking, and having a plain-knit portion at the top of the stocking above the lacework, substantially as described.

60 8. A machine-knit seamless stocking having lacework on the back as well as on the front of the stocking, a plain-knitted portion

preceding the lacework, and a plain-knitted heel, bottom of the foot and toe, substantially as described.

65

9. A machine-knit seamless stocking having open-work on the back and on the front of the stocking, a plain-knitted portion preceding the lacework, a plain-knitted heel, bottom of foot and toe, and a plain-knitted portion between the lacework and the toe of the stocking, substantially as described.

70 10. A machine-knit seamless stocking having open or lace work upon the top of the foot of the stocking and having plain solid knitting between said lacework and the top of the stocking, substantially as described.

75 11. A machine-knit seamless stocking having open or lace work on the top of the foot of the stocking and solid plain knitting above 80 the lacework, substantially as described.

12. A machine-knit seamless stocking having open or lace work on the top of the foot of the stocking and solid plain knitting preceding said open or lace work and solid plain 85 knitting following said lacework, substantially as described.

13. A machine-knit seamless stocking having open or lace work on the top of the foot of the stocking and having solid plain knitting 90 between said open or lace work and the top of the stocking and solid plain knitting between the open or lace work and the toe of the stocking; substantially as described.

14. A machine-knit seamless stocking, knit 95 in one continuous operation, having open or lace work on the back and on the front of the stocking with plain knitting above the open or lace work, substantially as described.

100 15. A machine-knit seamless stocking knit in one continuous operation having open or lace work upon the top of the foot of the stocking and plain knitting above said open or lace work and plain knitting between said open or lace work and the toe of the stocking, 105 substantially as described.

110 16. A machine-knit seamless stocking having a toe, foot and leg portion formed of a continuous thread or threads knit in one operation, and having the entire leg portion 115 formed of sections of open or lace work alternated with plain sections, with portions of plain loops between the open or lace work and the top of the stocking and between the open or lace work and the toe of the stocking, the heel bottom of the foot and toe portions being also composed of plain loops, substantially as described.

In testimony whereof I affix my signature in the presence of two witnesses.

GEORGE H. GILBERT.
